UNITED STATES PATENT OFFICE.

HERBERT L. WEIGEL, OF BUFFALO, NEW YORK.

DEVICE FOR HOLDING RUGS OR OTHER ARTICLES.

1,161,559.

Specification of Letters Patent.

Patented Nov. 23, 1915.

Application filed December 14, 1914. Serial No. 877,187.

To all whom it may concern:

Be it known that I, HERBERT L. WEIGEL, a citizen of the United States, residing at Buffalo, in the county of Erie and State 5 of New York, have invented certain new and useful Improvements in Devices for Holding Rugs or other Articles, of which the following is a specification.

My invention relates to a device for holding 10 rugs, carpets and the like on a line during the process of beating or cleaning and one object thereof is to provide a simple article of this nature made from a single piece of material and one which will be 15 simple and durable and cheap to manufacture.

Another object is to provide a device of the character stated which will securely hold 20 a rug or carpet on a line and prevent the same from sagging or in any way pulling loose from the line.

With the above and other objects in view, the present invention consists in the combination and arrangement of parts to be hereinafter more fully set forth, illustrated in the accompanying drawings, and particularly pointed out in the appended claims, it being understood that changes may be made 25 in the form, proportion, size and minor details without departing from the spirit or sacrificing any of the advantages of the invention.

Referring to the accompanying drawings illustrating my invention, and forming a 30 part of this specification, and in which like letters of reference indicate corresponding parts in each of the views: Figure 1 is a perspective view of the holder unapplied. Fig. 2 is an end view with the holder applied. Fig. 3 is a face view of the holder in the 35 act of being applied. Fig. 4 is a face view of a pair of holders applied.

In the drawings wherein is illustrated a preferred embodiment of my invention, the 40 numeral 1 designates a sheet metal or other plate or the like which forms the body of the device. This body portion is provided at one end with a projection or lug 2 struck up from the material of the body and being 45 preferably rectangular in shape. At the opposite end of the body portion 1 is formed a second projection or lug 3 also struck out of the said body portion, and being preferably triangular in shape. The projections 50 2 and 3 are preferably in horizontal alinement. Between the projections 2 and 3 is

arranged a third projection or lug 4 also struck from the metal body and being preferably rectangular in shape, which projection is located nearer the projection 2 than 55 the projection 3 and lying in a plane somewhat higher than the plane of the said projections 2 and 3.

The projections 2 and 3 are bent outward from the body portion and at a point intermediate their length bent downward, while the projection 4 is bent outward from the body portion and then bent upward intermediate its length. By this construction 60 three oppositely disposed wedge shaped 70 grooves are provided, one by each projection, for the reception of a line, rope, or the like.

As stated, the projection 3 is preferably 75 triangular in shape whereby an incline 5 is provided along one edge thereof. By means of this inclined edge the rope or line can be easily inserted in the wedge shaped groove of the said projection.

The plate 1 is curved rearwardly a short 80 distance along one longitudinal edge as shown at 6. This is to facilitate handling the device.

In the use of the device the carpet, rug or other material to be cleaned, beat or 85 otherwise treated or manipulated, is first thrown over the line. Then the projection 2 of the plate 1 is clamped over the rug and line as shown in Fig. 3. The plate is then given an upward movement until the projection 4 strikes the rope. Upon further upward movement of the plate, the rope will be bent around the projection 4 and securely wedged in the groove thereof. The rope will next come in contact with the inclined 90 edge 5 of the projection 3 and will ride up the inclined edge until it snaps into place in the wedge shaped groove provided by projection 3. Another plate is then applied to 95 the rug, or other article on the opposite side, as shown in Fig. 4, and the same held firmly in position. By having the projection 4 nearer the projection 2 it will be seen that a greater leverage is obtained and consequently a greater tension can be put on the 100 line, rope or the like, thereby holding the plate on the line securely.

What I claim is:—

1. An article of the class described comprising a sheet metal plate with three projections struck therefrom, one of the projections being located at one end of the 110

plate and a second projection located at the other end of the plate, the third projection intermediate the two end projections and being closer to one than to the other, the 5 projections at each end being curved outwardly and downwardly, with the intermediate projection curved outwardly and upwardly, the aforesaid plate being turned rearwardly along one longitudinal edge to 10 facilitate handling of the said plate.

2. An article of the class described comprising a sheet metal plate with three projections struck up therefrom, one projection at one end of the plate and a second 15 projection at the other end of the plate, said end projections being curved outwardly and downwardly and being in direct alinement, the third projection curved outwardly and upwardly and intermediate the two end 20 projections but being closer to one than to the other and being situated above the two end projections, so as to engage and deflect

the line and thereby hold the plate securely on the line.

3. An article of the class described comprising a sheet metal plate with three projections struck up therefrom, one projection at one end of the plate, and a second projection at the other end of the plate, with a third projection intermediate the two end 25 projections, the projection at one end of the plate and the intermediate projection being rectangular in shape, and the projection at the opposite end of the plate being triangular in shape, thereby forming an incline 30 along one edge of the said opposite end projection to facilitate the engagement of the plate with a line.

In testimony whereof I affix my signature in presence of two witnesses.

HERBERT L. WEIGEL.
